(57) **CLAIM**

I claim the ornamental design for a sloped-roof toy building element, as shown.

DESCRIPTION

FIG. 1 is a left perspective view of a sloped-roof toy building element, showing my new design.

FIG. 2 is a top view thereof.

FIG. 3 is a left-side view thereof; and,

FIG. 4 is a bottom perspective view thereof.

1 Claim, 1 Drawing Sheet

FIG. 1

FIG. 2

FIG. 3

FIG. 4
